UNITED STATES PATENT OFFICE.

RAYMOND D. SMITH, OF SCARSDALE, NEW YORK, ASSIGNOR, BY MESNE ASSIGNMENTS, TO TREMONT PRODUCTS CORPORATION, OF BOSTON, MASSACHUSETTS, A CORPORATION OF MASSACHUSETTS.

LAMP SOCKET.

Application filed March 15, 1922. Serial No. 543,880.

My invention relates to fixtures for lamp sockets and particularly to simple and inexpensive means for converting an ordinary fixture socket into a candle fixture.

My invention will be best understood from the following description and accompanying drawings of one specific embodiment of my invention which I have selected for illustrative purposes, while the scope of my invention will be particularly pointed out in the appended claims.

In the drawings:

Fig. 1 shows an elevation of a fixture constructed according to my invention and applied to an ordinary socket fixture; and

Fig. 2 is a similar elevation with parts in section.

Referring to the drawings I have indicated at 1 the fixture socket to which parts are to be applied to convert said socket into a candle fixture. This fixture socket comprises an exterior portion 3 of small diameter and a portion 5 of larger diameter separated from the smaller diameter portion by a shoulder portion 7. Internally of the socket 1 is a screw socket shell 9.

In the embodiment of my invention which I have selected for illustration, on the socket fixture 1 I place a member 11, which member is provided with a centrally located aperture 13 of such diameter that when the member is slipped over the small diameter portion of the socket fixture, the edges of said perforation will rest on the shoulder 7 of the socket fixture. Above the member 11 I provide a tubular member 15, the interior diameter of which is such that the tubular member may surround the small diameter portion 3 of the socket fixture. Although the member 11 and member 15 may be otherwise constructed, I have shown them for convenience of manufacture formed as separate members, and the member 15 in the form of a plain cylindrical tube abutting the upper surface of the member 11, the latter of which I have shown in the form of a cupped disk. The member 15 preferably is formed of insulating material, as for example, paper treated to harden it and render it fireproof.

At the upper portion of the tube 15 and interiorly thereof I mount a screw shell 17 which forms a socket for receiving the base 19 of a lamp 21. Internally of the lower

portion of the tube 15 I mount a screw shell 55 23 which forms the exterior of a screw plug for engaging the socket shell 9 of the fixture socket 1.

Each screw shell 17 and 23 I have shown provided with a flared portion 25 and a flange 27, the flanges in each case snugly fitting the interior walls of the tube 15. For further insuring a satisfactory connection between the flanges 27 and the tube, the former are prick-punched at 29 or are otherwise treated to have the material thereof forced into the walls of the tube.

At the bottom of each screw shell I support a button 31 of insulating material, for example, of porcelain, which buttons in the embodiment of my invention selected for illustration are provided with bevelled edges 33 to which the material of the screw shells is caused to conform.

Each button is provided with a central perforation 35, which carries a sput 37. The lower sput forms a contact for engaging the leaf spring or other contact 39 of the socket fixture 1, while the upper sput secures in an obvious manner the leaf spring 80 contact 41 to the associated button.

It will be noticed by the above construction that I have provided at the upper portion of the tube 15 a lamp socket for receiving the lamp base 19 and at the lower portion thereof a screw plug for engaging the socket fixture 1.

For placing the lamp socket and screw plug carried by the tube 15 in electrical communication I extend a wire 43 or other conductor through the respective spouts and solder its ends to said spouts. The screw shells 17 and 23 are placed in electrical communication by means of a strip 45 of copper foil or other conducting material, which strip is placed along the inner wall of the tube with its ends beneath the flanges 27 of the screw shells. Preferably, the flanges adjacent the strip 45 are prick-punched to better insure electrical contact between said strip and flanges. The strip, however, may be soldered to the flange or other part of the shell and if desired the conductor 43 may be made rigid enough to cause the upper lamp socket to be supported by the screw plug in which case neither the screw shell 17 or 23 need be attached to the tube 15.

Although I have described for purposes

of illustration one specific embodiment of my invention, it is to be understood that I am not limited thereby to the particular mechanical details mentioned but that within the scope of my invention wide deviations may be made therefrom without departing from the spirit of my invention.

Claims:—

1. An attachment for an electric light fixture to convert the appearance of same to that of a candle with its holder, embodying in combination with the lamp socket of said fixture composed of a lower relatively large mounting end and of an upper relatively small receptacle end encompassed by a jacket containing material to insulate the same,—an imitative candle stem having a hollow bottom end adapted to telescopically surround the portion of said jacket that encompasses the said receptacle end of the socket thereby to expose only the mounting end of said socket said stem carrying centrally of its hollow end a screw plug to be received into said socket,—and a flange fitting supported above the exposed mounting end of said socket and shaped and positioned relative to said candle stem to resemble a candle drip cup.
2. The combination with a lamp socket including in end to end relation a cylindrical receptacle portion and a supporting body portion of larger diameter than said receptacle portion and a shouldered jacket surrounding both said portions,—of a hollow upright cylindrical tube of proportions to resemble a candle and adapted to telescopically encompass only that length of said jacket which surrounds the receptacle portion of said socket and having its bottom end above and in proximity to the jacket shoulder, said tube carrying interiorly thereof, and interconnected electrically, means at its top end to hold a lamp and at its bottom end a plug base to be received into said receptacle portion of the socket.
3. An attachment for an electric light fixture to convert the appearance of same to that of a candle with its holder, embodying in combination with the lamp socket of said fixture composed of a lower relatively large mounting part and of an upper relatively small receptacle part encompassed by a jacket containing material to insulate the same,—an imitative candle stem having a hollow bottom end adapted to telescopically surround said jacket thereby to conceal the true length of said socket and carrying centrally of said hollow end a screw plug to be received into said socket,—and a flange member supported on said socket at the junction of the said relatively large and relatively small parts thereof and shaped to resemble a candle drip cup.
4. An attachment for an electric light fixture to convert the appearance of same to that of a candle with its holder, embodying in combination with the lamp socket of said

fixture composed of a lower relatively large mounting end and of an upper relatively small receptacle end encompassed by a jacket containing material to insulate the same,—an imitative candle stem having a hollow bottom end adapted to telescopically surround the portion of said jacket that encompasses the said receptacle end of the socket thereby to expose only the mounting end of said socket said stem carrying centrally of its hollow end a screw plug to be received into said socket,—and a flange fitting supported above the exposed mounting end of said socket and shaped and positioned relative to said candle stem to resemble a candle drip cup.

5. An attachment for an electric light fixture to convert the appearance of same to that of a candle with its holder, embodying in combination with the lamp socket of said fixture comprised of a lower relatively large mounting end and of an upper relatively small receptacle end, both said ends being encompassed by a jacket containing material to insulate the same and formed with a shoulder at the junction of said two socket ends,—an imitative candle stem having a hollow bottom end adapted to sleeve down over the upper end of said jacket and terminate at the shoulder thereof thereby to conceal the true length and original shouldered appearance of said socket, and carrying centrally of said hollow end a screw plug to be received into said socket,—and a removable ring flange having a hole of a size intermediate the diameters of said jacket at respectively opposite sides of its said shoulder thereby to be supported on said shoulder and formed to resemble a candle drip cup.

6. In a device of the character described, the combination with a lamp socket having its wall composed of a threaded shell, with an outer casing and an insulating lining separating the two, a tube-like attachment representing a candle, a lamp receptacle carried interiorly of said attachment, with the open end of said receptacle facing outwardly, a screw plug having an end contact and a shell, said screw plug being carried interiorly of said attachment at the end thereof opposite said lamp socket, and said screw plug having its contact facing outwardly and its shell spaced from said attachment a sufficient distance to permit insertion of said wall of the lamp socket in the annular space between said shell and said attachment.

7. The combination with an electric lamp socket having an insulative housing with a relatively large diameter portion and a relatively small diameter portion, of a candle-like lamp-holding stem in part surrounding said small diameter casing portion and its housing and a flange-like fitting surrounding said housing near the base of said stem to represent a candle drip cup.

8. A fitment attachable to an electric lamp socket to resemble a candle and its holder embodying in combination with said socket and with an inner lamp receptacle thereof and an outer shouldered jacket of reduced diameter in its portion surrounding said receptacle, an imitative candle structure adapted to be received by said receptacle in place of the lamp and having a straight tubular casing extended longitudinally to surround and conceal said reduced diameter portion of the socket jacket, said casing terminating substantially at the shoulder on said jacket the parts of said jacket below its said shoulder being exposed to cause the same to appear as a holder for said candle structure. 40
9. Fitments attachable to an electric lamp socket switch to resemble a candle and its holder embodying in combination with said socket switch and with an inner lamp receptacle thereof and an outer shouldered jacket of reduced diameter in its portion surrounding said receptacle, an imitative candle structure adapted to be received by said receptacle in place of the lamp and having a straight tubular casing extended longitudinally to surround and conceal said reduced diameter portion of said jacket, said casing terminating substantially at the shoulder on said jacket, and a flange mountable upon said shoulder to represent a drip cup,—the parts of said socket below said flange being exposed to appear as a holder for said candle structure, and to permit the protuberance of a control for said socket switch. 45
10. The combination with a threaded lamp receptacle shell closely encompassed by an insulative jacket, of a lamp receptive candle stem including a threaded plug base adapted to screw into said shell in place of the lamp, the cylindrical wall of said stem being extended as a skirt at its bottom end to encompass said plug base and shell and the contiguous portions of said jacket, while leaving other portions of the latter exposed to appear as a holder for said candle stem. 50
11. The combination with a threaded lamp receptacle shell closely encompassed by an insulative jacket, of a lamp receptive candle stem including a threaded plug base adapted to screw into said shell in place of the lamp, the cylindrical wall of said stem being extended as a skirt at its bottom end to encompass said plug base said shell and the contiguous portions of said jacket while leaving other portions of the latter exposed to appear as a holder for said candle stem, together with a detachable flange also surrounding said jacket and positioned substantially at the bottom of said stem to represent a candle drip cup. 55
12. In combination with an electric lamp socket embodying a threaded lamp receptacle mounted on the socket body and enclosed by an open-ended cylindrical jacket of relatively small diameter in its portion surrounding said receptacle and of relatively large diameter in its portion surrounding said body, detachable fitments resembling a candle with its drip cup mountable upon said lamp socket and adapted when so mounted to surround enough of said jacket to conceal the said small diameter portion and to expose the said large diameter portion thereof. 60
13. In testimony whereof, I have signed my name to this specification. 65
